United States Patent Office.

PETER PHILIP AND FRANKLIN PHILIP, OF STOCKPORT, NEW YORK.

Letters Patent No. 98,706, dated January 11, 1870.

IMPROVEMENT IN MACHINE FOR MAKING WIRE HEDDLES.

The Schedule referred to in these Letters Patent and making part of the same.

To all whom it may concern:

Be it known that we, PETER PHILIP and FRANKLIN PHILIP, of Stockport, in the county of Columbia, and State of New York, have invented a certain Improvement in Machines for Making Heddles; and we do hereby declare that the following is a full, clear, and exact description thereof, reference being had to the annexed drawings, making part of this specification, in which—

Figure 1 is a plan view of the machine.

Figure 2 is a longitudinal vertical section thereof, on line $z z$, fig. 1.

The same letters are used in both figures in the designation of identical parts.

Our invention relates to a machine for making heddles for looms; and our improvement consists in combining, with the ordinary mechanism thereof, a lever provided on its outer end with a point or tooth, and so arranged upon one of the twisting-jaws, that the tooth shall, at the beginning of the operation, be thrust between the wires close to the eye-forming jaws, and press or crowd the twist toward such forming-jaws in order to make the angles of the eye, at the junction of the wires, less acute than they can be made without such tooth, and so that, as the twisting progresses, such tooth shall be gradually withdrawn from between the wires; all as will be more fully set forth herein-after.

To enable those skilled in the art to make and use our invention, we will proceed to describe its construction and operation.

In the drawings—

A represents the bed-plate or frame-work of the machine, having suitable standards or blocks, A¹ and A², formed upon or secured to it, in which the mandrels have their bearings, there being usually two of them employed, arranged opposite to, and in one axial line with each other. In front of the block A¹, a pedestal, A², is arranged upon the bed-plate, to form a support for the eye-forming jaws which are pivoted in the upper portion thereof.

Through the centre of the mandrel B, a hole of sufficient size is bored, or otherwise formed, through which the wires are passed; and deep longitudinal grooves are formed in them to receive the holding and twisting-jaws.

C C' represent the holding and twisting-jaws, constructed and arranged in the mandrel in the ordinary manner.

D represents the sliding collar by which the jaws are opened and closed. It is partly embraced by a fork, E¹, lying in a groove therein, and which is actuated by a reciprocating rod, E, upon which it is arranged in connection with a spring, E², in the manner shown.

E³ and E⁴ represent the eye-forming jaws pivoted in the pedestal A³. The jaw E³ is provided with a projection upon its upper face, around which the eye of the heddle is formed.

A more specific description of the above-enumerated parts is deemed unnecessary, as they are well-known devices, and form no part of our present invention, and may be sufficiently understood by reference to the drawings.

Heddles, as heretofore constructed by the old-style machines, had more or less acute angles at the crossing of the wires, which is an objectionable feature, because they are liable to catch the warp and break it, or check the steady progress of the threads whenever a knot or unevenness is encountered. Sometimes the eyes are formed by spreading of the wires subsequent to their being twisted together, whereby the angles may be made less acute, but they are always more or less roughened and marred in this way.

To obviate these objections, we employ a lever, F, binged to one of the twisting-jaws C, and provided, at its forward end, with a point or tooth, F¹, which is thrust between the wires, between the twisting and eye-forming jaws, for the purpose of crowding or pressing the twist toward the said forming-jaws, to give the desired shape to the eye, as well as to take up slack wire to be used in forming the twist, so that the twist may be made very tight without unduly straining and injuring the surface of the wires.

The lever F is so arranged on the twisting-jaw that its point F¹ is retained between the wires of the heddle until the twist is sufficiently pressed against the forming-jaws, and sufficient slack taken up, when it is withdrawn. The lever is arranged on a reduced portion of one of the twisting-jaws pivoted upon the same pin on which the jaw turns. Its forward arm is provided with the tooth or point F¹, as above stated, and its other arm being extended to just beyond the inner face of the block A¹ in a nearly horizontal direction, is turned abruptly outward, terminating near the bend of the twisting-jaw, as shown.

Where this short end, which is marked F² in the drawings, joins the main portion of the lever, a spur or projection, f, is formed, which is engaged by a catch or hook, G, the angled point of which is so constructed as to be capable of impinging against the horizontal edge of the spur f, in order to press the point F¹ between the wires, as also to press against the vertical edge of said spur, to keep the point out of the wires. The catch is pivoted at its outer end to the twisting-jaw, as shown, and is actuated by the spring G'.

H is a wedge-shaped piece of metal fastened to the inner side of the block A¹, and in such a position, that as the mandrel is revolved, the forward edge of the part F² of the lever F shall come in contact with such

wedge or incline, and thereby the lever gradually turned, so as to withdraw its tooth from between the wires. When the lever has been thus turned, its spur *f* has escaped from the angled point of the catch, which now impinges against the vertical edge of such spur, holding the lever in such a position that the upper edge of its forward arm is flush with the surface of the mandrel, so that, on opening the jaws, it will be forced against the bearing of the mandrel, and turned sufficiently to cause the point of the catch to again hook under the spur *f*, and thrust its tooth *F'* again between the wires.

Having thus described our invention,

What we claim, and desire to secure by Letters Patent, is—

1. In combination with the twisting-jaws of a ma-

chine for making heddles, a point or tooth which is first thrust between the wires for the purpose of crowding the twist toward the eye-forming jaws, and also for the purpose of taking up slack wire to be used in forming the twist, and then gradually withdrawn from between the wires, substantially in the manner set forth.

2. The combination of the twisting-jaws *C'*, lever *F*, with point or tooth *F'*, hook *G*, spring *G'*, and incline *H*, all arranged to operate substantially in the manner set forth.

PETER PHILIP.
FRANKLIN PHILIP.
